ATTORNEY.

UNITED STATES PATENT OFFICE.

WALTER REICE GREGG, OF ST. LOUIS, MISSOURI.

WINDOW-SASH LIFTER.

Application filed June 13, 1924. Serial No. 719,839.

To all whom it may concern:

Be it known that I, WALTER REICE GREGG, a citizen of the United States, residing at St. Louis, in the State of Missouri, have 5 invented certain new and useful Improvements in Window-Sash Lifters, of which the following is a specification.

This invention relates to closure operators and pertains particularly to an apparatus 10 for use primarily in connection with windows to assist in shifting or raising of the sash within the window.

The primary object of this invention is the provision, in a manner as hereinafter set 15 forth, of a window sash lift designed to make the raising of window sash easy, when such sash are not supported by the usual sash weights.

A further object of the invention is the 20 provision, in a manner as hereinafter set forth, of a window sash lifter adapted to be set when the sash is lowered so that upon raising of the sash, the device will tend to draw up upon the same to give a lift thereto.

The invention contemplates the provision 25 of a horizontal shaft adapted to be positioned within the top portion of a window casing, the said shaft carrying thereon a horizontally positioned spiral spring and further carrying a pair of pulleys about 30 each of which a sash cord is wound, one cord being connected to an upper sash and the other cord being connected to a lower sash, and these pulleys are revolved when 35 either of the sash is raised or lowered, the lowering of either sash acting to twist the spring carried upon the mentioned shaft to place the same under tension, there of course being a connection between the pulleys and 40 the spring, so that when it is desired to raise the sash the spring, due to the tension under which it has been placed through twisting, will act to revolve the pulley connected to the sash which is being raised, to 45 wind up the sash cord and thus assist in the raising of the sash.

A further and final object of the invention is the provision, in a manner as hereinafter set forth, of a window sash lift 50 of simple design, strong and durable, and efficient for the purpose for which constructed, not complicated in structure, and inexpensive to manufacture and install.

The invention will be best understood 55 from a consideration of the following detailed description taken in connection with

the accompanying drawings forming part of this specification, with the understanding that the invention is not confined to any strict conformity with the showing of the drawings but may be changed and modified so long as such changes and modifications mark no material departure from the salient features of the invention as expressed in the appended claim.

In the drawings:

Figure 1 discloses the upper portion of a window frame in elevation, a portion thereof being broken away to show the application of the device embodying this invention.

Figure 2 is a vertical transverse sectional view upon the line 2—2 of Figure 1.

Figure 3 is a detail in elevation, of the device embodying this invention, a portion thereof being shown in section for better illustration.

Figure 4 is a section upon the line 4—4 of Figure 3.

Figure 5 is a section upon the line 5—5 of Figure 3.

Figure 6 is a detail, showing in side elevation, one of the supporting brackets used to retain the device in position.

Referring now to the drawings in detail, wherein like numerals of reference indicate corresponding parts throughout the several views, a window sash is indicated at 8 having the usual surrounding front plates 1 and rear plates 2 connected by and closed between the inner edges by the inner face or 90 wall plate 3, which extends about the inner side of the frame formed by the face plates 1 and 2. The inner wall 3 of the frame has extending thereabout the spaced front, intermediate, and rear beadings 4, 5 and 6 respectively, as shown in Figure 2, and these front and intermediate beadings 4 and 5 separate and act to guide the lower sash 7 in the frame, and the intermediate and rear beadings 5 and 6 serve to retain and guide 100 the upper sash 8 in the frame. Each sash has formed in each side at the upper portion thereof, the usual sash cord slots 9 and 10, each being enlarged at its lower end for the purpose which will become apparent 105 hereafter, and the slot 10 of the upper sash 8 is of greater depth than the slot 9 in the lower sash 7 and the purpose for this will become apparent as the description proceeds.

The device embodying this invention comprises a pair of spaced inner and outer

brackets 11 and 12, respectively, each bracket being formed in two portions, each portion comprising a leg 13 having the lower end thereof turned outwardly in a horizontal plane as at 14 and the upper portion of the leg 13 has formed upon its inner face an abutment 15 which forms the lower part of and from which extends a semi-circular member 16 which terminates in a vertical ear 17. These vertical ears are secured together, when the two leg members are in position together, by means of screws 18 and the abutments 15 are likewise secured together by a like screw member. The angular extensions or feet 14 of each half of a bracket are connected to a corresponding half of the other bracket by means of the connecting bar 19 which serves to retain the halves of the bracket members in proper spaced relation. Each foot of each half of each bracket member has formed therethrough an aperture 20 for the passage of a retaining means (not shown). Upon reference to Figure 3 it will be seen that one of the bracket members is larger than the other and that the ring or bearing formed by the two halves of one bracket is of greater size than that formed by the two halves of the other bracket. The completed bracket shown in Figure 6 has not been referred to as either bracket 11 or 12, as this showing in this figure is only to designate the parts of the two brackets, as they are identical with the exception of the size.

Clamped between the halves 16 of the bracket 12 is a stub shaft 21 the inner end of which carries an annular collar 22 which bears against the inner side of the bracket 12 to prevent longitudinal movement of the stub shaft 21 between the members 16. The outer portion of this stub shaft 21 is also formed to provide an annular collar 23 which bears against the outer face of the bracket 12.

Formed integral with the outer end of the stub shaft 21 is a pulley 24, the inner side of which carries a relatively wide annular flange 25 the outer face of which merges with the collar 23 carried upon the outer end of the shaft 21. This stub shaft 21 and pulley 24 have formed through the longitudinal center thereof a bore 26 through which there extends to revolve freely therein a shaft 27. This shaft extends, as before stated, through the bore 26 of the members carried in the bracket 12 to the bracket 11 where the end of the shaft is received between the members 16 of this bracket to revolve therebetween. This shaft 27 has formed thereabout and integral therewith, a collar 28 which is adapted to bear against the inner face or side of the bracket 11. This collar 28 has extending inwardly therefrom an apertured lug 29, the use of which will become apparent as the descrip-

tion proceeds. A similar apertured lug 30 is formed upon the inner face of the collar 22.

The shaft 27 is of such length that when in the position above described with one end supported to revolve between the members 16 of the bracket 11, the other end will extend well beyond the outer end of the pulley 24, and this other end has one side flattened slightly and for a short distance inwardly from the end as indicated at 31.

A second pulley 32 is secured to this flattened end of the shaft 27, this pulley being provided with end flanges 33 of the same diameter as the flange 25 upon the pulley 24, the inner of the flanges 33 of the pulley 32 serving as a flange also for the outer end of the pulley 24. Tapped through the drum of the pulley 32 is a screw member 34, the head of which is flush with the periphery of the drum and the inner end of which contacts with the flattened surface 31 of the shaft 27 to secure the pulley upon the shaft.

The flange 25 and the inner one of the flanges 33 each has formed therethrough, adjacent the drum body of the pulley upon which they are carried, an aperture 35.

Carried about the body of the shaft 27 between the brackets 11 and 12, is a coiled spring 36 one end of which is attached to the apertured ear or lug 30 carried upon the collar 22 and the other end of which is secured in the apertured lug 29 carried by the collar 28 as clearly shown in Figure 3 of the drawings.

The pulleys 24 and 32 are each adapted to have wound thereupon sash cords 37 and 38 respectively, the ends of which are secured in the apertures 34 and 35.

When in operation, there are two of the devices just described located in the top of the window casing as indicated in Figure 1, these devices being in reverse position one with respect to the other and as shown, positioned so that the inner pulley 24 of each device will be positioned directly above the side member of the sash frame. The cord 37 leading from the inner pulley 24 is passed downwardly through apertures in the top of the window casing and into the groove 10 of the upper window sash as shown in Figure 1, while the cord 38 from the outer pulley 32 is passed downward through the top of the window casing and secured in the groove 9 of the lower sash 7. It will now be seen that by making the slot 10 of greater depth than the slot 9, the cords would pass directly down from their respective pulleys without curving over any portion of the window frame.

When the device is installed, it is installed with both sash raised, that is, the upper sash in its normal closed position and the lower sash 7 in its raised or opened position, and both cords 37 and 38 are wound up upon

their respective pulleys. When the supporting brackets 11 and 12 have been secured in position within the window frame, and the cords 37 and 38 have had their ends secured 5 as at 39 within their respective slots, the sash 8 is lowered, thus drawing upon the cord 38 to unwind the same from the pulley 32 by causing this pulley to revolve and revolve the shaft 27, which in turn revolves 10 the collar 28 to twist that end of the spring 36 to which the collar 38 is attached, placing the same under tension. The spring 36 is not twisted to such a degree that the tension under which it is placed will be sufficient to 15 revolve the shaft and pulley 32 to raise the window, but the tension is such that when one desires to raise the lower sash 7, the spring will come into play to revolve the shaft 27 and the pulley 32 to wind thereon 20 the cord 38 and thus assist in lifting the sash. If the upper sash is lowered from its normal closed position, it will thus draw upon the cord 37 and revolve the drum 24 and the stub shaft 21 to twist the other end 25 of the spring 36 which is connected to the apertured ear 30 carried upon the collar 22 and when it is desired to restore this sash to its normal position, the spring will thus act to revolve the drum 24 and assist in re- 30 turning the sash to its closed position.

From the foregoing description, it may be seen that a new and very novel structure results which is very efficient for the purpose for which constructed.

Having thus described my invention what 35 I claim is:

A sash lifter of the character described, comprising a tubular stub shaft, a pair of annular flanges thereabout, one at one end and the other about the central portion 40 thereof, a pair of supporting bearings, one engaging said shaft between said flanges, a main shaft extending freely through said stub shaft and having one end supported in the other bearing, a flanged pulley upon and 45 keyed to the other end of said main shaft and abutting said stub shaft, the inner flange of said pulley constituting an outer flange for the end of the stub shaft to set up in connection therewith an inner pulley, a 50 spring element wound about said main shaft and having one end attached to that flange upon the end of the stub shaft and its other end connected to said main shaft, and hanger cords wound about said pulleys and adapted 55 to be connected to the upper and lower sash of a window for the purpose set forth.

In testimony whereof, I affix my signature hereto.

WALTER REICE GREGG.
